DESIGN.

—o—
W. L. JACOBS.

CARPET.

No. 17,486.

Patented July 26, 1887.

UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,486, dated July 26, 1887.

Application filed June 15, 1887. Serial No. 241,431. Term of patent 3½ years.

To all whom it may concern:

Be it known that I, WINTHROP L. JACOBS, of East Orange, New Jersey, have invented a new and original Design for Carpets, of which the following is a specification; reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The main feature of my design consists in the irregular grouping of the various geometrical or flower forms into distinct groups, in each one of which a given geometric form is repeated a number of times. These groups are irregularly disposed over the surface of the carpet upon any suitable groundwork.

Group A is composed of a number of cross forms placed in different positions, so as to be assembled more compactly.

25 Group B is composed of a number of flower forms substantially circular in shape, with more or less irregular serrations around the edge.

Group C is composed of a number of geometric forms, each one having the appearance 30 of an assemblage or mass of squares. In the intervening spaces between the figures of this group are smaller cross forms.

Group D is composed of a number of compound figures, each one having the general 35 outline of a triple diamond.

Group E is composed of a number of geometric forms resembling squares or blocks, with an indentation on each side.

Group F is composed of a number of balloon-shaped figures.

Group G is composed of a number of skeleton figures, each one having the general shape of a diamond and the group being arranged in a diamond form.

Group H is composed of a number of figures, each one consisting of an assemblage of circular forms and having a pebbled appearance.

Interspersed between these groups are other 50 groups, all clearly shown in the photograph.

What I claim as new, and desire to secure by Letters Patent, is—

1. The design for carpets, consisting of the group D, substantially as shown.
2. The design for carpets, consisting of the group F, substantially as shown.
3. The design for carpets, consisting of the groups A B C D E F G H and the other groups, substantially as shown.

W. L. JACOBS.
